DOUBLE-ACTION RELAY

Roy E. Wells, Seaforth, near Sydney, Australia

Application April 5, 1949, Serial No. 85,541
In Australia April 14, 1948

2 Claims. (Cl. 200—98)

1

This invention relates to a double action relay adapted to operate two separate sets of contacts adapted to remain in engagement under the action of potential applied to a pulsing line.

An object of this invention is to provide a relay with double action under the influence of two separate coils which, when an impulse is passed over an impulse line, will operate two separate sets of contacts, both sets of contacts remaining in engagement during the entire period of time that potential is applied to the pulsing line.

According to the invention when potential is disconnected, one of the said sets of contacts remains in engagement under the influence of a spring action, whereas the other set of spring contacts will become disengaged under the influence of their own spring resistance.

Upon potential being re-applied to the same impulse line, the second of the said pair of coils will be energized and the contacts already held in contact under the influence of the said spring action, will be disengaged by the pull of this second coil and two other sets of contacts will now become engaged for that period of time that potential remains applied to the impulse line.

When potential is disconnected one of this second two sets of contacts will remain engaged under said spring action and the other set of contacts will become disengaged under the influence of their own spring resistance.

The two coils mentioned are preferably of a solenoid type directly opposed to each other and with their cores connected by a rivet or pin so that the two cores shall combine while travelling either in one direction or the other, according to which coil is energised.

In the course of the travel of the said cores the rivet or pin joining these cores, engages and operates two U shaped slotted levers which are pivotally mounted on a spindle running parallel to and below the rivet or pin, the slot in one of said levers being so dimensioned as to give only slight clearance for the said rivet, whereas the slot in the other U shaped lever is dimensioned to give appreciably larger clearance, so that the rivet shall travel a certain distance before actual operation of the said other lever.

From this it will be understood that the U shaped lever with the wider slot will travel in each direction over an appreciably shorter arc than the U shaped lever with the narrow slot.

A protrusion or roller extends from each U shaped lever to operate two sets of contacts, and is so arranged that each U shaped lever operates

2

one set of contacts in each direction of travel according to which coil is energized.

Attached to the U shaped lever with the wider slot is a spring loaded extension piece, the springs of which are so arranged as to have maximum tension at that point where said U shaped lever is in the central position between the two coils, the said spring being mounted in such manner that, when the U shaped lever with the wider slot is moved off centre in either direction, the said spring will assist in applying pressure to force the said U shaped lever off centre and to hold it in that direction until such time as the said lever is pulled back across the centre line by the influence of the opposing coil.

The wiring of the contacts and coils is so designed that the impulse line is open to that coil which last operated, but, through the contacts held in engagement by the spring loaded extension piece, is closed to the opposing coil so that, when the potential is applied to the impulse line, that coil which did not operate on the last impulse will be energized and so pull both U shaped levers and, in doing so, it will close the contacts on the side where the U shaped lever has the narrow slot before breaking the opposing contacts, held by said spring loaded extension piece of the said lever with the larger slot.

In this way through hook-up contacts on the side of the U shaped lever with the narrow slot, the coil, at the time energized will remain so, until such time as the impulse line is open, and the contacts closed by the U shaped lever with the narrow slot, spring open.

At the same time the U shaped lever with the wide slot will have been pulled over the centre line and, by the previously described spring action together with the pull of the solenoid, will have engaged its contacts on the other side and also have so prepared the circuit to operate the opposite coil after the impulse line has first been opened.

In order that the invention may be more readily understood, reference will now be made to the accompanying drawings wherein:

Figure 1 is a diagrammatic view illustrating one form of the present invention with the lower solenoid energised.

Figure 2 is a similar view to Figure 1 with the upper solenoid energised.

Figure 3 is a detail side view on line 3—3 of Fig. 1 with some of the parts omitted, illustrating the spring operated mechanism of the device shown in Figs. 1 and 2.

Figs. 4 and 5 are, respectively, perspective views

on an enlarged scale of parts of the device shown in Figs. 1-3.

Fig. 6 is a section view taken on line 6-6 of Figure 2.

In accordance with the present invention the relay illustrated diagrammatically in the drawings comprises a pair of single acting solenoids 10, 11, the coils of which are alternately energized from an impulse line 12.

The respective solenoids 10, 11, are mounted upon a frame 13, see Figure 3, and have a common plunger 14 which is slotted centrally and has a pin 15 disposed medially in said slot.

The frame 13 pivotally supports U shaped members 16 and 17, the inner limbs 18 and 19 respectively of which are bifurcated to engage the pin 15, the bifurcated portion 18 of the U shaped member 16 approximates the diameter of the pin 15 but the bifurcated portion 19 of the U shaped member 17 is wider than the diameter of the said pin 15, and provides for lost motion or delayed action when the pin 15 is moved relatively to the said U shaped member 17, there being little relative movement between the U shaped member 16 and the pin 15 when the latter is moved in either direction by the plunger 14 due to operation of the respective solenoids 10 and 11.

The outer ends of the U shaped members 16 and 17 have insulated rollers 20 and 21 respectively mounted thereon and the said U shaped member 17 has a spring loaded tension piece 22 mounted on a frame pivot 23 and having transverse arms 24, 25 the extremities of which latter engage loop springs 26 which are pivotally carried by the frame 13 and are engaged by notches 27 formed in said arms 24, 25. The U-shaped members 16 and 17 are shown at an enlarged scale in Figs. 5 and 4, respectively.

Figure 3 shows how the flexing springs 26 and the spring loaded tension piece 22 hold and tend to force the U shaped lever 17 off centre. The two springs 26 as illustrated are pivoted on the centre line of the spindle 23 on which the levers 16, 17 are pivoted, so that the pivoting holes 28 of the springs 26, the notches 27 for the springs 26 in tension arms 24, 25 and the centre of the spindle 23 are all in line A-B when the U shaped lever 17 is in a neutral position.

As soon as the U shaped lever 17 is off centre in either direction, the springs 26 exert pressure on arms 24 or 25 to force it positively off centre.

The said insulated roller 20 is adapted to alternately operate a first and a second group of distributing contacts and the said insulated roller 21 is adapted to alternately operate a first and a second set of holding contacts.

The second impulse distributing contact group or bank comprises a single pole double throw spring contact 29 having an insulated pad which is in engagement with roller 20 of the U shaped lever 16 and is disposed between a first stationary contact spring 30 and a second stationary contact spring 31, said spring contact 29 being adapted to engage a second insulated pad 57 disposed upon spring contact 32 and move it into engagement with a fixed contact 33 which is adapted to be connected to remote apparatus such as any signalling or recording device. The contact springs 29 to 33 are termed hereinafter the fourth set.

The third set of the second impulse distributing contact group or bank comprises a single pole double throw spring contact 34 having an insulated pad 51 which is in engagement with the insulated roller 20 of the U shaped lever 16

and is disposed between a first stationary contact spring 35 and a second stationary contact spring 36, said spring contact 34 being adapted to engage a second insulated pad 59 disposed upon spring contact 37 and move it into engagement with a fixed contact 38 which is adapted to be connected to remote apparatus referred to above.

In their normal position, the spring contacts 29 and 34 engage respectively the fixed contacts 30 and 35 and spring contacts 32 and 37 are out of engagement with fixed contacts 33 and 38.

The first set of holding contacts comprises a spring contact 39 having an insulated pad 60 which is in engagement with the roller 21 and is adapted to be engaged with a fixed contact 40. A second spring contact 41 is engaged by an insulating pad 61 disposed to be operated by spring contact 39 and is adapted to engage with fixed contact 42, adapted to be connected to remote apparatus referred to above.

The second set of holding contacts comprises a spring contact 43 having an insulated pad 62 which is in engagement with the roller 21 and is adapted to engage with a fixed contact 44, a second spring contact 45 is engaged by an insulating pad 63 disposed to be operated by spring contact 43 and is adapted to engage with fixed contact 46 adapted to be connected to remote apparatus referred to above.

In operation assuming that the mechanism is in the position seen in Figure 1, an impulse is sent over conductor 12 to springs 29 and 34 to normally closed contacts 30 and 35 to conductors 47 and 48 to contacts 40 and 44.

Contact 44 is disengaged with its mating spring contact 43 because springs 26 through the extension 24, 25 are holding the wide slotted lever 17 in an off centre position so that the roller 21 is holding contact spring 43 out of engagement with a contact 44.

In the case of the other circuit on conductor 47 to contact 40 it will be seen that contact is made through the normally closed contacts to spring 39 to conductor 49 to a terminal 50 of solenoid coil 10 thence to earth; said coil 10 becomes energized and pulls the plunger 14 together with pin 15 downwardly and said pin 15 in turn operates levers 16 and 17.

Because of the narrower slot in lever 16 engaged by the pin 15, the roller 20 engages the pressure pad 51 of spring 34 and breaks its contact with contact 35 and makes contact with contact 36 before lever 17 with the wide slot is engaged by pin 15 and is moved so that its roller 21 allows the spring contacts 43 to engage contact 44 also before said roller 21 moves 39 out of engagement with 40.

It will be seen from this, that solenoid 10 is now provided by potential via conductor 12, spring contact 34, contact 36 and conductor 52 to terminal 50, whereas solenoid coil 11 is deprived of potential at the open contacts 34 and 35.

Solenoid coil 10 will now remain energized as long as potential is applied to the pulsing line 12, but immediately potential is broken from line 12, solenoid coil 10 will become de-energized and release its pull on plunger 14 allowing lever 16 to return to a central position under pressure of contact spring 34 which will now open the contacts 34 and 36 and reclose contacts 34 and 35.

However, now closed contacts 44 and 43 will remain closed and now open contacts 40 and 39 will remain open under pressure of the springs

26 on extensions 24, 25 of the wide slotted lever 17.

It will now be seen that when another impulse is received by conductor 12, see Figure 2, solenoid 10 is disconnected from potential by the open contacts 40 and 39, also 34 and 36, whereas solenoid coil 11 received potential from conductor 12, contacts 34 and 35, conductor 48, contacts 44 and 43 and conductor 53 to terminal 54, and as the plunger 14 moves in the opposite direction and lifts spring 29 through lever 16 and roller 20 into engagement with contact 31, then potential will be supplied to coil 11 via conductor 12, contacts 29 and 31 and conductor 55 to terminal 54 before contacts 40 and 39 remake or contacts 44 and 43 are broken by lever 17 and roller 21.

From this it will be seen that plunger 14 is operated by coils 10 and 11 in alternate directions for each impulse received on impulse line 12.

It will be understood that a plurality of spring contacts such as (32, 33), (37, 38), (41, 42), and (45, 46) may be employed for various purposes such as operating, signalling and recording devices or starting and stopping motors or other electrical equipment.

It will be appreciated that various modifications may be made without departing from the spirit of the invention as defined in the following claims; for example, relay coils may be used instead of solenoids 10 and 11, in which case the plunger 14 is replaced by an armature having extension pins on each side thereof in place of the pin 15 used on the plunger 14.

It will also be appreciated that the solenoid coils do not have to be arranged to pull in opposite directions as illustrated in Figures 1 and 2 as they may, for example, be arranged side by side.

I claim:

1. A double action relay, comprising in combination, a first coil; a second coil arranged in alignment with said first coil; a plunger common to said coils and operable alternately in one and the other of two opposite directions according to the energization of said coils; a first spring-loaded lever pivotally mounted adjacent to said plunger and having a slot; a pin rigidly connected to said plunger and engaging the slot of said first lever for forcing the same off center in either of two directions according to the energization of said coils, the slot of said first lever having a width exceeding the diameter of said pin so as to allow said plunger to return to a central position between said coil while said first lever remains in an off-center position; a first bank of spring contacts including a first set and a second set arranged adjacent to said first lever for engagement and disengagement with one another, respectively, according to the direction in which said first lever is forced off center; a

second lever devoid of a spring load and pivotally mounted adjacent to said plunger, said second lever having a slot engaged with a close fit by said pin whereby said second lever is forced off center in either of two directions according to the energization of said coils; and a second bank of spring contacts including a third set and a fourth set arranged adjacent to said second lever and being adapted to be engaged and retained in engagement for the duration of the operation of said plunger by said coils and to return to a disengaged position immediately upon de-energization of said coils.

2. A double action relay as claimed in claim 1, said first set and said second set each including a stationary contact spring and a movable contact spring moved into and out of contact with said stationary contact spring by said first lever, said third set and said fourth set each including a first stationary contact spring, a second stationary contact spring, and a single pole double throw contact spring moved into and out of contact with said first and second stationary contact springs by said second lever, said first coil being electrically connected to said movable contact spring of said first set and said second stationary contact spring of said third set, said second coil being electrically connected to said movable contact spring of said second set and said stationary contact spring of said fourth set, said stationary contact springs of said first set and said second set being electrically connected, respectively, to said first stationary contacts of said fourth set and said third set; and an impulse carrying conductor connected to said single pole double throw contact springs of said third set and said fourth set, whereby said coils are alternately connected to said impulse conductor over said contact springs in response to the motion of said plunger.
